UNITED STATES PATENT OFFICE.

ELIZABETH L. ROWLES, OF GOODHUE, MINNESOTA.

BOOK-COVER PROTECTOR.

1,238,342.

Specification of Letters Patent. Patented Aug. 28, 1917.

Application filed June 2, 1915. Serial No. 31,726.

To all whom it may concern:

Be it known that I, ELIZABETH L. ROWLES, a citizen of the United States, residing at Goodhue, in the county of Goodhue and 5 State of Minnesota, have invented certain new and useful Improvements in Book-Cover Protectors, of which the following is a specification.

My present invention relates to a new and 10 improved book cover protector which embodies in its organization, a flexible cover protector designed to extend about the entire outer surface of the sides and back of the book, reinforcing tabs to protect the 15 respective corners of the sides and a reinforcing strip to protect the back; the latter engaging the back and prevents the accidental displacement of the cover during the opening and closing movement of the book.

20 The main object resides in the provision of a device of the above nature which is simple, compact and durable and which is constructed so that it will be neat in appearance and manufactured at a minimum cost.

25 Various other objects and advantages will become apparent during the continuance of the following description.

The above and other objects which will 30 become apparent, are accomplished by such means as are shown in their preferred form in the accompanying drawings, described in the following specification and then more specifically pointed out in the appended claims.

35 In the accompanying drawings wherein like characters designate like parts throughout the several views;

Figure 1 is a plan view of my improved 40 cover protector showing the same as in an open position.

Fig. 2 is a sectional view taken on line 2—2 of Fig. 1.

Fig. 3 is a vertical sectional view of my 45 invention shown applied to the cover of a book.

Fig. 4 is a detail view showing the back reinforcing member when first cut from the stock.

Fig. 5 is a fragmentary view showing the 50 upper right hand portion of Fig. 3 slightly enlarged.

In constructing the cover protector, a section of flexible material is provided, such 55 for instance as a heavy Manila paper. The paper is cut to form a substantially rectangular body 10 carrying tapering exten-

sions 11 and 12 adjacent its respective ends, and tabs 13 and 14 upon its respective upper and lower edges. The extensions and tabs are preferably bent to lie in the position indicated in Fig. 1, so that the ends of the extensions such as designated at 12' will overlie the adjacent portion of the tabs 13 and 14. The overlying portions 12' of the extensions may be secured to the adjacent 60 tab by any suitable means. However in the drawings I have shown the same stitched as at 15, in order to more clearly set forth the 65 construction of my invention.

After the extensions and tabs have been 70 secured in this position, it will be noted that suitable pockets are formed in the protector 10 which may conveniently receive the respective covers of a book. In order to more securely hold the tabs and extensions in this 75 position, and to obviate the danger of the same becoming unloosened or torn during the insertion of the sides of the back, reinforcing members 16 are employed and arranged to extend about the respective inner 80 edges of the tabs and extensions in the manner clearly illustrated in Fig. 1. The reinforcing strips may be attached to the adjacent structure in any desired manner, yet I have found that the same may be quickly 85 attached by stitching.

In consistence with the foregoing, I have devised a suitable reinforcing means which may be constructed of celluloid or the like bendable material. This means consists 90 generally of the substantially angular-shaped clips 17 which fit snugly about the corners of the protector structure as clearly illustrated in Figs. 1 and 3, not only protecting the cover of the book, but preventing 95 the corners of the sides of the book from becoming injured. If it is so desired, these clips may be permanently attached to the cover by suitable means.

I have also devised an improved reinforcing strip 18 which may be formed of celluloid or the like material which is designed 100 to protect the back of the book when my improved cover is arranged in place. The strip 18 is provided with a tapering extension 19 at each end thereof which is preferably bent into the position shown in Figs. 1 and 3 to extend over the upper edge of the back of the book and snugly engage the inner surface thereof. The strip is secured to 110 the cover protector through the medium of the spaced apart tongues 20 which are car-

ried adjacent the extensions 19 and which are bent to engage the cover protector as shown in Fig. 1. It will also be noted that the tongues 20 serve to retain the respective ends of the reinforcing members 15 and 16 in position, consequently preventing the same from becoming loosened or raveling. The strip 18 may also be attached to the body of the cover such as gluing the same in position or by employing metallic clips or fasteners such as pointed out in connection with the clips 17. From the construction of the strip 18, it will be noted that the same may be stamped from an integral section of material consequently reducing the cost of manufacture.

In applying my improved protector to a book, one side of the book is first inserted into the pocket provided therefor to the left of Fig. 1, after which the book is moved in the usual manner so as to permit its other side to be positioned in the opposite pockets of the protector. When thus arranged, the extension 19 may be engaged with the back 25 of the book as pointed out hereinbefore and as illustrated in Fig. 3, whereby the protector will be securely retained in place. After the cover protector has been attached in this manner, the book may be opened or closed 30 with the usual ease and the cover will not in any way impede such opening or closing movement.

From the foregoing it will be appreciated that my invention is exceedingly simple in 35 construction and it is believed that the utility of the reinforcing clips and the strip 18 will be readily recognized.

In reducing my invention to practice I 40 find that the form referred to herein as the most practical and preferred embodiment is the most efficient, but realizing that certain conditions will necessarily vary in concurrence with the adoption of my device, I desire to emphasize the fact that various minor

changes in the details of construction and in 45 the proportion of parts may be resorted to when required without sacrificing any of the advantages of my invention as defined in the appended claims.

Having thus fully described my invention, 50 what I claim as new and desire to secure by Letters Patent is:

1. A book cover protector comprising a body for covering the sides of a book, and a reinforcing strip positioned intermediate 55 the length of the body and having gripping tongues and end extensions extending therefrom, the gripping tongues being bent to grip the protector and connect the reinforcing strip therewith, the extensions being 60 bent to engage the back of the book and connect the protector therewith.

2. A reinforcing body for a book cover protector comprising a resilient strip having tongues at opposite ends bent back thereupon to embrace the upper and lower edges 65 of a protector, and extensions at opposite ends of the strip bent back to pass over the upper and lower edges of the back of a book and engage the inner face thereof to connect 70 the protector with the back of a book.

3. A reinforcing body for the back engaging portion of a book cover protector comprising a strip having tongues and end extensions extending therefrom, the tongues 75 when bent back upon the strip extending to engage the book cover protector and connect the reinforcing body therewith, and the extensions when bent back upon the strip extending to engage the back of a book and 80 connect the cover protector with the back of a book.

In testimony whereof I affix my signature in presence of two witnesses.

ELIZABETH L. ROWLES.
